UNITED STATES PATENT OFFICE.

BURTON I. REED, OF CONCORD, NEW HAMPSHIRE.

DESIGN FOR A BADGE OR BUTTON.

59,284.

Specification for Design.

Patented Oct. 4, 1921.

Application filed March 26, 1921. Serial No. 455,993. Term of patent 7 years.

To all whom it may concern:

Be it known that I, BURTON I. REED, a citizen of the United States, residing at Concord, in the county of Merrimack, State of New Hampshire, have invented a new, original, and ornamental Design for Badges or Buttons, of which the following is a specification, reference being had to the accompanying drawings, forming a part hereof.

The figure is a plan view of a badge or button showing my new design.

I claim:

The ornamental design for a badge or button, as shown.

BURTON I. REED.
